UNITED STATES PATENT OFFICE.

JOHN S. CLARKE, OF PINCKNEYVILLE, KENTUCKY.

FURNACE FOR EVAPORATORS.

1,304,542.

Specification of Letters Patent. Patented May 27, 1919.

Application filed April 10, 1918. Serial No. 227,737.

To all whom it may concern:

Be it known that I, JOHN S. CLARKE, a citizen of the United States, residing at Pinckneyville, in the county of Livingston and State of Kentucky, have invented certain new and useful Improvements in Furnaces for Evaporators, of which the following is a specification.

This invention relates to furnaces for evaporating apparatus used in the concentration of syrups.

The object of the invention is to provide a simple and efficient furnace of this character constructed so that it may be turned to always present a draft opening to the wind and thereby insure a continuous draft and a steady fire to effect speedy concentration of the syrup.

Another object is to construct a furnace so that the heat may be controlled to prevent liability of burning of the syrup.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a top plan view of a furnace constructed in accordance with this invention,

Fig. 2 is a longitudinal section taken on the line 2—2 of Fig. 1,

Fig. 3 is a transverse section taken on the line 3—3 of Fig. 1, and

Fig. 4 is a transverse section through one of the wheels.

In the embodiment illustrated, the furnace constituting this invention comprises a body 1, here shown rectangular in form, with cross bars 2 arranged in the bottom thereof in longitudinally spaced relation with their ends projecting beyond the opposite sides of the body.

Diagonally disposed braces 3 are also arranged on the bottom of the body 1 intersecting each other about midway the length of said body as is shown clearly in Fig. 1. The opposite ends of these braces 3 also project beyond the sides of the body and underlap the projecting ends of the cross bars 2, these lapping ends being provided with aper-

tures for the passage therethrough of wheel supporting spindles 10 which are swiveled in their bearings. These spindles have their lower ends threaded for adjustable engagement with wheel carrying members. In these members 12 are mounted the wheels 11, the upper ends of these members being designed to rest against the lower faces of the projecting ends of the brace bars 3 as shown at 13 in Fig. 3. These spindles 10 also project through apertures in laterally extending brackets 4 carried by the upper faces of the side walls of the body 1. These brackets 4 as shown, are L-shaped in form, and the spindles 10 have swiveled connection with their laterally extending arms 5 to permit the ready turning of the wheels. These spindles being mounted to revolve in their bearings, provide for the turning of the furnace so as to retain the draft opening shown at 6 always toward the wind so that a continuous draft will be furnished to the furnace to render the heat uniform.

The body 1 has an opening 7 in its bottom near its front end in which a grate, not shown, is designed to be mounted, while its rear end has a cross plate 8 with an opening 9 in which a combustion pipe, not shown, is to be mounted.

A horizontal partition 14 is mounted in the rear portion of the body 1 as is shown clearly in Fig. 2 so that the flame may be directed either above or below it for controlling the heat supplied to the evaporating apparatus which it is understood is designed to be mounted over said body 1 and preferably to rest on the top thereof.

This partition 14 terminates at its rear end in a plane in advance of that occupied by the opening 9 and is inclined downwardly and forwardly as shown clearly in Fig. 2 so as to provide proper draft. This partition 14 and the damper 15 to be described, are both preferably coated with asbestos to prevent all danger of the syrup being scorched during the last stages of the evaporating process.

A hinged damper is mounted at the front end of the partition 14 and is adapted to be swung either up or down as shown in Fig. 2 for controlling the direction the flame is to pass. This damper 15 which extends transversely across the body 1 is mounted on a pintle 16 which is revolvable in bearings carried by the side walls of the body 1 and has one end projecting beyond one side of the

body and provided with a crank handle 17 for operating the damper. Damper stops 18 are carried by the inner face of the opposed side walls of the body 1 as shown 5 clearly in Figs. 1, 2 and 3, and are preferably composed of brackets. Obviously, however, these stops may be of any desired construction, their object being to limit the upward swinging movement of the damper 10 as shown in dotted lines in Fig. 2.

The wheels 11 are preferably dish-shaped as shown in cross section in Fig. 4, with grooves 11' in their peripheries.

Six wheels are here shown on which the 15 body 1 is mounted, but obviously, any desired number may be used according to the size of the furnace to be supported.

From the above description it will be obvious that this furnace while very simple in 20 construction and cheap to manufacture, may be readily transported from place to place and the body 1 thereof may be positioned at different inclines by adjusting the wheel spindles 15 in the brackets 5, and by 25 providing revoluble wheels therefor it may be turned at any desired angle according to the direction in which the wind is blowing so that the draft opening 6 will always face 30 the wind for the reason above described.

The foregoing description and the drawings have reference to what may be considered the preferred or approved form of my 35 invention. It is to be understood that I may make such changes in construction and arrangement and combination of parts, materials, dimensions, *et al.*, as may prove ex-

pedient and fall within the scope of the claimed invention.

Having thus fully described my invention, what I claim as new and desire to secure by Letters Patent, is:—

In an evaporating furnace, a substantially rectangular body member, longitudinally spaced cross bars secured to the bottom thereof and projecting at opposite ends beyond its side walls, diagonally disposed brace bars also arranged on the bottom of said body and intersecting intermediately of their ends, said bars projecting at their ends beyond the sides of said body and apertured forming combined brace members and spindle bearings, the apertured ends of the diagonal bars underlapping the ends of the cross bars, the cross bars also having apertures to register with those in the diagonal bars, apertured brackets carried by the side walls of said body in vertical alinement with the apertured ends of said bars, spindles revolvably mounted in the registering apertures of said bar ends and brackets, 55 wheel carrying members having threaded sockets, the lower ends of said spindles being threaded for detachable and adjustable engagement with said wheel carrying members.

In testimony whereof I affix my signature in presence of two witnesses.

JOHN S. CLARKE.
